Chrysler Corporation, Highland Park, Mich., a corpora-
tion of Delaware

Filed July 5, 1960, Ser. No. 61,227

Term of patent 7 years

(Cl. D48—32)

Fig. 1 is a front elevational view of an automobile tail lamp bezel showing my new design;

Fig. 2 is a top plan view thereof;

Fig. 3 is a side elevational view thereof;

Fig. 4 is a side elevational view of the side opposite to that illustrated in Fig. 3;

Figs. 5 and 6 are sectional views taken on the lines 5-5 and 6-6, respectively, of Fig. 3; and

Figs. 7 and 8 are sectional views taken on the lines 7-7 and 8-8, respectively, of Fig. 4.

The dominant features of my design reside in the full line portion of the drawing.

I claim:

The ornamental design for an automobile tail lamp bezel, substantially as shown and described.
